TROLLEY WIRE FIXTURE

Samuel S. Matthes, Mansfield, Ohio, assignor to
 The Ohio Brass Company, Mansfield, Ohio, a
 corporation of New Jersey

Application May 10, 1949, Serial No. 92,411

13 Claims. (Cl. 191—37)

1

The present invention relates generally to trolley wire fixtures and is more particularly concerned with novel and very useful trolley fittings, including crossing devices and switches.

In a conventional trolley crossing a trigger is disposed between adjacent runners and against one of said runners for engagement with a current collector travelling along that runner. This trigger is moved by the current collector away from the runner along which the collector is running, and a bridging member associated with the trigger through a lever carried by a body with which the runners are suitably integrally formed, is thrown into position to receive the travelling current collector and guide it across the body to an opposing aligned runner. The bridging member, however, is not always in alignment with the proper runners to safely transfer the current collector across the device and, therefore, is likely to be derailed and damaged during its traverse of the crossing. Furthermore, if there is any substantial variation in the size of current collectors used with a given crossing, jamming and derailing for lack of adequate clearance in the throat of the device between the runners is likely. Still another disadvantage of these crossings is the noise incident to their operation.

According to the present invention, these various shortcomings and difficulties of the prior art will be entirely eliminated. Additionally, these advantages may be obtained without any attending economic or structural disadvantage, and without any increase in maintenance or repair costs.

For a better understanding of this invention, those skilled in the art are referred to the following detailed description taken in conjunction with the drawings accompanying and forming a part of this specification, in which:

Fig. 1 is a bottom plan view of a crossing device embodying the present invention in a preferred form;

Fig. 2 is a fragmentary perspective view of the device of Fig. 1, showing it typically associated with trolley wires and a current collector;

Fig. 3 is a top plan view of the device of Fig. 1;

Fig. 4 is a side elevational view of the device of Fig. 1 in partial section;

Fig. 5 is an exploded perspective view of one of the triggers of this invention; and

Fig. 6 is a section taken on line 6—6 of Fig. 1.

From the foregoing it will be apparent that this invention generally embodies a trolley crossing in which the current collector-engaging triggers are resiliently expandable and compressible. Also,

2

in accordance with the better practice of this invention, special stationary guide means overlapped by the bridging member, and shock-absorbing and impact-deadening means, are incorporated in the crossing.

More particularly, a typical crossing of my invention, as shown in Figs. 1 to 4, inclusive, comprises a body 10 having a plurality of integral eye lugs 11 spaced along its side, and a pair of spaced, 10 downwardly directed flanges 12 defining a channel in which a current collector may travel between the ends of the body. The eye lugs are provided for engagement with supporting wires or cables in the usual manner. Two pairs of 15 straight U-shaped runners 14 extending divergently from opposite ends of the body are formed integrally with said body and their under portions are disposed for engagement with a current collector 17 (Fig. 2). Body 10 is further provided 20 with two spaced slots 19—19' and a centrally located aperture 20 to receive moving parts, as will be described, and with two threaded apertures 21 near its ends and between adjacent runners 14.

25 A bridging member 24, including the usual copper shunt E, is secured movably to body 10 by a center pin 23 extending through aperture 29. This bridging member 24 carries between each of its ends and its mid-section two pins 27—27', which extend upwardly through slots 19—19' for operative engagement with actuating mechanism generally indicated as M. Bridge member 24, furthermore, has end portions 25, the upper part of each of which is partially cut away for a purpose to be described, and the bridge 24 is so dimensioned as substantially to extend from one opposed runner 14 to another and thus provide an essentially continuous current collector guide-way of uniform shape and size from end to end of the crossing. The height of the runners and bridging member is such that the flanges of the current collector do not ride on body 10.

The actuating mechanism, which accounts for motion of the bridge to meet the guide-way requirements of current collectors traversing the crossing, comprises a pair of levers 30—30' which are supported pivotally between their ends by support pins 31 screwed into apertures 21, and are pivotally attached at their adjacent bifurcated ends to roller pins 27—27'. At their remote ends, these levers are each provided with a trigger 35 which is disposed between adjacent runners 14, said levers being turned downwardly 55 at said remote ends and projecting through

spaces provided between the intermediate portions of the runners.

Triggers 35 each comprise a pair of contact shoes 36 carried pivotally on a pin 38 fastened to the remote end of each of the levers, said shoes having lug or web portions 39 near one end and on the inside faces and apertures in these webs 39 are in register and receiving pin 38 holds the shoes assembled to the levers. Shoes 36 are resiliently disposed apart at their other ends by means of a spring 40 located between and bearing upon opposed inner faces of the shoes, being retained by opposed short pins 42 integrally formed with the shoes. An abutment means 44 integrally formed with each lever 30—30' is disposed at the remote extremity of the lever for engagement with the normally closed end portion of the triggers, to position the shoes and assure at all times engagement of the current collector with the triggers.

A cam lever 46 having a sharp peaked cam surface 47 to assure that the mechanism will not have a dead center position, is fulcrumed at one end adjacent to the side of body 10 and is connected at its other end to a carriage bolt 49 resiliently fastened to the body by a spring 50 which has a loop at one end hooked through an eye lug 51 (Fig. 3) extending upwardly from the top of body 10, whereby the tension of the actuating means may be adjusted. Roller pin 27 carries a roller 55 in the end of lever 30 and carries below the said lever and in slot 18 a bumper ring 56 of rubber or rubber-like material, but suitably of any soft non-metallic substance such as cloth or leather. This bumper is so dimensioned as to engage with the body when the bridging member comes into alignment with one or the other of the opposed sets of runners 14.

Guide means 61 which assures the proper alignment of runners 14 and bridge 24 comprises a generally triangular shaped extension at the inner side of each runner 14. The outer face of each said guide means 61 is substantially in line with the outside surface portion of the adjacent runner and of partial height of the runner. This guide means 61 is cast integral with the body 10 and the end of runner 14 in each instance. The end portions 25 and 61 overlap.

From the foregoing description, it will be apparent that in the operation of this device, current collector 17 travels along one or the other of a pair of runners, as indicated in Fig. 2, and the flange 17' thereof engages a trigger 35 and moves it toward and into engagement with the other runner whereby roller 55 is carried beyond the peak of cam lever 46 so that spring 50 becomes effective and automatically throws the end of lever 30 over-center thereby moving the bridging member 24 into position in alignment with the proper runner to receive the current collector. This action is all practically instantaneous, assuming an average speed of travel of the current collector. Consequently, the shoe is compressed almost at the same instant that flange 17' comes into contact therewith, if clearance between the shoe and the said opposing runner is inadequate to permit free passage of the current collector. The collector thus is permitted to travel on through the throat defined by the runners. When the collector reaches the bridge 24, it is guided on the bridge by one of the extensions 61, providing the bridge is not in exact alignment with the runner. Further travel of the current collector brings it to the inner end of the opposing runner and on through the throat

of the other pair of runners where it may compress the engaged shoe and spring 40 of the other trigger if the collector flange does not have free passage. The impact involved upon the throwing of the bridge is taken up, and the noise normally incident to the operation is damped, by rubber bumper ring 56, as described above.

In Fig. 6 is shown a section on the line 6—6 of Fig. 1 through the runners and the trigger to show the normal relative position of the runners and shoes of the trigger before and after the current collector has passed through the crossing.

The construction of the trigger permits one to make the angle of divergence of the runners much smaller than where the trigger is a one-piece unit. With the trigger herein disclosed it is possible to produce a crossing device with the divergent angle of the runners as small as 10°.

The width of current collectors is not standardized and may vary considerably on the same system; therefore, it has been found that a device made for the smallest width of current collector, will also operate with one of a reasonably greater width due to the yielding of the shoes 36.

For instance take a device which has been designed for a minimum angle of divergence between runners and for a current collector of a predetermined width, the space 62 between the shoe 36' and 14' (Fig. 6) will just permit the free passage of the collector flange but should a wider collector or one with thicker flanges attempt to pass through the said space, the collector would be dewedired if the trigger were unyielding; note in Fig. 6 the shoe 36'' is in engagement with the runner 14''. But the spring 40 would permit the shoe 36' to yield thus increasing the space 62 and the wider current collector would then pass through safely.

The bolts 63 may be used to secure projecting end members to the runners for smooth passage of the current collector onto and off of the body member 10. Such end members differ depending upon the size and shape of the trolley wire. Such end member is shown in Fig. 6, U. S. Patent 2,053,965.

From the foregoing description, it is also clear that a plurality of stationary guide means and shock-absorbing and dampening means may be provided in accordance with this invention, where special circumstances require the additional expense. Likewise, other routine modifications may be made without departing from the spirit of this invention or the scope of the appended claims.

I have shown and described my invention as applied to an overhead fitting to guide a current collector at the crossing of two trolley wires, but it will be evident that the same operating mechanism as herein shown and described may be applied to actuate the bridging member on a trolley fitting of the type shown in U. S. Patent 2,053,965 cited above.

Having thus described the present invention so that others skilled in the art may understand the same, I state that what I desire to obtain by Letters Patent is set out in what is claimed.

What is claimed is:

1. A trolley fitting comprising a body, a plurality of runners extending from the body for engagement with trolley wires, a bridging member movably carried by the body for defining with two opposed runners a guide-way for a current collector, and means for operating the bridging member including a lever fulcrumed between its ends and pivoted near one end to the bridging

member, and a trigger secured to the other end of the lever and disposed between two adjacent runners for engagement with the current collector and motion in response to force applied by said collector travelling along one of said runners, said trigger comprising a pair of shoes hinged together and resilient means between the shoes resiliently holding the shoes apart.

2. A trolley fitting comprising a body, a plurality of runners extending from the body for engagement with trolley wires, a bridging member movably carried by the body for defining with two opposed runners a guide-way for a current collector, and means for operating the bridging member including a lever fulcrumed between its ends and pivoted near one end to the bridging member, and a trigger secured to the other end of the lever and disposed between two adjacent runners for engagement with the current collector and motion in response to force applied by said collector travelling along one of said runners, said trigger comprising a pair of shoes hinged together near one end and resilient means between the shoes resiliently holding apart the other ends of the shoes.

3. A trolley fitting comprising a body, a plurality of runners extending from the body for engagement with trolley wires, a bridging member movably carried by the body for defining with two opposed runners a guide-way for a current collector, and means for operating the bridging member including a lever fulcrumed between its ends and pivoted near one end to the bridging member, and a trigger secured to the other end of the lever and disposed between two adjacent runners for engagement with the current collector and motion in response to force applied by said collector travelling along one of the runners, said trigger comprising a pair of shoes hinged together near one end, a spring between the shoes resiliently holding the shoes apart at the other end, and abutment means associated with the lever to engage the shoes and limit to a predetermined amount the spread of the shoes.

4. A trolley fitting comprising a body, a plurality of runners extending from the body for engagement with trolley wires, stationary guide means for a current collector associated with the body and disposed adjacent to and in substantial alignment with one of the runners, a bridging member movably carried by the body and overlapping the guide means for defining with two opposed runners a guide-way for a current collector, and means for operating the bridging member including a lever fulcrumed between its ends and pivoted near one end to the bridging member, and a trigger secured to the other end of the lever and disposed between two adjacent runners for engagement with the current collector and motion in response to force applied by said collector, said trigger comprising a pair of shoes hinged together between their ends and resilient means between the shoes resiliently holding the shoes apart.

5. A trolley fitting comprising a body, a plurality of runners extending from the body for engagement with trolley wires, a bridging member movably carried by the body for defining with two opposed runners a guide-way for a current collector, and means for operating the bridging member including a lever fulcrumed between its ends pivoted near one end to the bridging member, a trigger secured to the other end of the lever and disposed between two adjacent runners for engagement with the current collector

and motion in response to force applied by said collector, and a soft non-metallic element between a portion of said body and the bridging member for engagement with these two parts to dampen impact shocks, said trigger comprising a pair of shoes hinged together between their ends and resilient means between the shoes resiliently holding the shoes apart.

6. A trolley fitting comprising a body, a plurality of runners extending from the body for engagement with trolley wires, stationary guide means for a current collector integrally formed with the body and in substantial alignment with a runner, a bridging member movably carried by the body and overlapping the guide means for defining with two opposed runners a guide-way for a current collector, and means for operating the bridging member including a lever fulcrumed between its ends and pivoted near one end to the bridging member, and a trigger secured to the other end of the lever and disposed between two adjacent runners for engagement with the current collector and motion in response to force applied by said collector travelling along one of the runners, said trigger comprising a pair of shoes hinged together near one end, a spring between the shoes resiliently holding the shoes apart at the other end, and abutment means integral with the lever to engage the shoes and limit spread of the shoes.

7. A trolley fitting comprising a body, a plurality of runners extending from the body for engagement with trolley wires, stationary guide means for a current collector integrally formed with the body and each runner and in substantial alignment with the runners, a bridging member movably carried by the body and overlapping the guide means for defining with two opposed runners a guide-way for a current collector, and means for operating the bridging member including a lever fulcrumed between its ends and pivoted near one end to the bridging member, a trigger secured to the other end of the lever and disposed between two adjacent runners for engagement with the current collector and motion in response to force applied by said collector travelling along one of said runners, and a rubber bumper carried by the bridging member for engagement with the body to cushion impact shocks, said trigger comprising a pair of shoes hinged together and resilient means between the shoes resiliently holding the shoes apart.

8. A trolley fitting comprising a body, a plurality of runners extending from the body for engagement with trolley wires, stationary guide means for a current collector integrally formed with the body and the opposed ends of each runner and disposed adjacent to and in substantial alignment with the runners, a bridging member movably carried by the body and overlapping the guide means for defining with two opposed runners a guide-way for a current collector, and means for operating the bridging member including a lever fulcrumed between its ends and pivoted near one end to the bridging member, a trigger secured to the other end of the lever and disposed between two adjacent runners for engagement with the current collector and motion in response to force applied by said collector travelling along one of said runners, and a rubber bumper carried by the bridging member for engagement with the body to cushion impact shocks, said trigger comprising a pair of shoes hinged together near one end, a spring between the shoes resiliently holding the shoes apart and

abutment means integral with the lever for engagement with the shoes to limit shoe spread.

9. Trolley fitting apparatus comprising a bridging member, a lever pivoted near one end of the bridging member for operating said member, a rubber bumper carried by the said member to cushion impact shocks, and a trigger associated with the lever to move said lever and bridging member under force applied by a current collector, said trigger being compressible and including a pair of opposed elongated shoes hinged together near one end, and a spring between the shoes and resiliently holding said shoes apart at the other end of the trigger.

10. Trolley fitting apparatus comprising a bridging member, a lever pivoted near one end of the bridging member for operating said member, and a trigger associated with the lever to move said lever and bridging member under force applied by a current collector, said trigger being compressible and including a pair of opposed elongated shoes hinged together between their ends, and resilient means between the shoes resiliently holding said shoes apart.

11. Trolley fitting apparatus comprising a bridging member, a lever pivoted near one end of the bridging member for operating said member, and a trigger associated with the lever to move said lever and bridging member under force applied by a current collector, said trigger being compressible and including a pair of opposed elongated shoes hinged together between their ends, resilient means between the shoes resiliently holding said shoes apart, and abutment means carried by the lever for engagement with the shoes to limit shoe spread.

12. Trolley fitting apparatus comprising a bridging member, a lever pivoted near one end of the bridging member for operating said member, and a trigger associated with the lever to move said lever and bridging member under force applied by a current collector, said trigger being compressible and including a pair of opposed

elongated shoes hinged together near one end, a spring between the shoes resiliently holding said shoes apart at their other end, and abutment means carried by the lever for engagement with the hinged ends of the shoes to limit the spread of the shoes.

13. An overhead trolley fitting to guide a current collector comprising a body, a plurality of runners extending from the body for engagement with trolley wires, a bridging member movably carried by the body for defining with two opposed runners a guide-way for a current collector, and means for operating the bridging member including a lever fulcrumed between its ends to 15 the body to move in a plane parallel to the plane of the body and pivoted near one end to the bridging member, a trigger secured to the other end of the lever and disposed between two adjacent runners for engagement with the current collector to move the said other end of the lever in either direction transverse to the body and to move the said one end of the bridging member in a plane parallel to the plane of the body in response to force applied to the trigger by the current collector depending on the direction of approach, and a soft non-metallic element between a portion of said body and the bridging member for engagement with these two parts to dampen impact shocks.
